Primary Examiner — John M Otte(74) *Attorney, Agent, or Firm* — Leydig, Voit & Mayer, Ltd.(57) **CLAIM**

The ornamental design for a display screen with a graphical user interface, as shown and described.

DESCRIPTION

FIGURE is a front elevation view of a display screen with a graphical user interface showing our new design. The outer broken lines illustrate the display screen and form no part of the claimed design. The remaining broken lines illustrate portions of the graphical user interface and form no part of the claimed design.

1 Claim, 1 Drawing Sheet

Employee Information	
Before beginning enrollment, all of your personal and benefit information must be complete. Please complete the required fields below, or, if the information has already been entered, please verify that it is correct. You'll need to agree to the information and then click Continue to the bottom of the page.	
Demographics First Name: ____ Last Name: ____ Middle Name: ____ Last Name: ____ Last Name: ____ Middle Name: ____ Nickname: ____ Social Security Number: ____ Date of Birth: ____
